CLAIM

The ornamental design for an architectural fixture, as shown and described.

DESCRIPTION

FIG. 1 is a bottom, front, right perspective view of an architectural fixture according to a first embodiment of our new design;

FIG. 2 is a top plan view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a bottom plan view thereof;

FIG. 8 is a top, front, right perspective view thereof;

FIG. 9 is a bottom, front, right perspective view of an architectural fixture according to a second embodiment of our new design;

FIG. 10 is a top plan view thereof;

FIG. 11 is a front elevation view thereof;

FIG. 12 is a right side elevation view thereof;

FIG. 13 is a rear elevation view thereof;

FIG. 14 is a left side elevation view thereof;

FIG. 15 is a bottom plan view thereof;

FIG. 16 is a top, front, right perspective view thereof;

FIG. 17 is a bottom, front, right perspective view of an architectural fixture according to a third embodiment of our new design;

FIG. 18 is a top plan view thereof;

FIG. 19 is a front elevation view thereof;

FIG. 20 is a right side elevation view thereof;

FIG. 21 is a rear elevation view thereof;

FIG. 22 is a left side elevation view thereof;

FIG. 23 is a bottom plan view thereof;

FIG. 24 is a top, front, right perspective view thereof;

FIG. 25 is a bottom, front, right perspective view of an architectural fixture according to a fourth embodiment of our new design;

FIG. 26 is a top plan view thereof;

FIG. 27 is a front elevation view thereof;

FIG. 28 is a right side elevation view thereof;

(Continued)

FIG. 29 is a rear elevation view thereof;
 FIG. 30 is a left side elevation view thereof;
 FIG. 31 is a bottom plan view thereof; and,
 FIG. 32 is a top, front, right perspective view thereof.
 The appearance of any portion of the architectural fixture
 between the break lines shown forms no part of the claimed
 design. The broken lines are for the purpose of indicating
 break lines and form no part of the claimed design. The
 dot-dash lines define the bounds of the architectural fixture
 and also form no part of the claimed design.
